CLAIM

The ornamental design for a linear actuator accessory control box, as shown and described.

DESCRIPTION

FIG. 1 is a perspective top view of a linear actuator accessory control box showing my new and ornamental design,

FIG. 2 is a perspective bottom view thereof,

FIG. 3 is a perspective top view thereof which is identical to FIG. 1 but with its cover depicted in an opened state,

FIG. 4 is a top plan view thereof.

FIG. 5 is an elevational left side view thereof,

FIG. 6 is an elevational right side view thereof,

FIG. 7 is a bottom plan view thereof.

FIG. 8 is a front view thereof; and,

FIG. 9 is a rear view thereof.

1 Claim, 3 Drawing Sheets
